CLAIM

The ornamental design for colored reciprocating saw blade, as shown and described.

DESCRIPTION

FIG. 1 is a perspective view of a colored reciprocating saw blade showing my new design;

FIG. 2 is a left side elevational view thereof;

FIG. 3 is a rear elevational view thereof;

FIG. 4 is a front elevational view thereof;

FIG. 5 is a right side elevational view thereof;

FIG. 6 is a top plan view thereof;

FIG. 7 is a bottom plan view thereof;

FIG. 8 is a perspective view of a second embodiment of a colored reciprocating saw blade showing my new design;

FIG. 9 is a left side elevational view thereof;

FIG. 10 is a rear elevational view thereof;

FIG. 11 is a front elevational view thereof;

FIG. 12 is a right side elevational view thereof;

FIG. 13 is a top plan view thereof; and,

FIG. 14 is a bottom plan view thereof.

The broken line showing of in FIGS. 8-14 is for illustrative purposes only and forms no part of the claimed design.

The drawings have been lined for color.
